UNITED STATES PATENT OFFICE.

AUGUSTE DELUBAC, OF LA BÉGUEDE, FRANCE, ASSIGNOR TO SOCIETE FRANCAISE DE LA VISCOSE, OF PARIS, FRANCE, A CORPORATION OF FRANCE.

APPARATUS FOR PRODUCING AND TREATING VISCOSE THREADS OR ARTIFICIAL SILK.

No. 928,777.

Specification of Letters Patent.

Patented June 1, 1909.

Application filed July 5, 1907. Serial No. 382,350.

To all whom it may concern:

Be it known that I, AUGUSTE DELUBAC, a citizen of the French Republic, residing at La Bégude, Department of Ardèche, France, have invented certain new and useful Improvements in Apparatus for Producing and Treating Viscose Threads or Artificial Silk, of which the following is a specification.

This invention has for its object a mechanism or apparatus for producing and treating, in separate threads, viscose obtained by treating cellulose with soda, sulfid of carbon and water. The thread obtained possesses a dye-absorbing power far superior to that of viscose thread obtained by the former means.

The thread as produced by the apparatus hereinafter specified has a uniformity of tone, the twisting of the thread being done after the fixing process, the elementary staples retain a certain amount of elasticity and do not constitute fixed spirals as in the case of thread twisted before the fixing process, as obtained by the old means. This has the result that to weave a given surface a less length of the same thread is required. The suppleness of the thread is obtained naturally without the addition of any chemical product whatever in the baths or in the solution of cellulose.

By simply regulating the air pressure, the standard of fineness desired to be spun is obtained automatically and consequently it is possible to manufacture much finer threads than by the old means. A great number of handlings of the thread in skein form are done away with, resulting in a diminution of the waste and of the risk of stripping the thread.

Figure 1 of the accompanying drawings is a diagrammatic view showing the general arrangement of the apparatus for carrying out the object of the invention. Figs. 2 and 3 are a side elevation and a front elevation respectively of one of the feed rollers of the apparatus. Fig. 4 is a front view of the drier. Fig. 5 is a sectional view of the drier.

The solution of cellulose termed viscose is contained in a closed reservoir 1; from this reservoir it is forced by the pressure of compressed air admitted by a pipe 3. The pipe 2 conveys the viscose from the reservoir 1 to a draw-plate 4 immersed in a coagulating bath 5. The pipe 2 is fully open and the supply is regulated solely by the constancy of the pressure of the compressed air. The thread

as soon as it has become coagulated in the bath 5 passes successively into the baths 6, 7 and 8. Bath 6 consists of water acidulated with 7% of sulfuric acid at a temperature of 70° C. The effect of this bath is to render the thread insoluble in water. Bath 7 consists of water at the ordinary temperature, with intense circulation, and is intended for the washing of the thread. Lastly, bath 8 contains water, ordinary soap, oil and soda intended to complete the neutralization of the thread and prevents its adhering to the drier.

In a manufacturing plant the viscose reservoirs 1 are installed in a basement with a constant temperature, below the engine. A certain number of draw-plates—about ten or fifteen—are supplied by the same reservoir and it is thus possible to give the whole of the viscose pipes exactly the same form and approximately the same length. It is thus easy to obtain an equal rate of supply with the pipe full open for the whole of the draw-plates, the pressure and frictional resistances being themselves equal; moreover it is possible to control the temperature of the viscose up to the point where the pipes issue above the floor of the workshop, which is a great advantage in the spinning of viscose. In its passage through the different baths the thread is supported by power-driven rollers 9, the circumferential speed of which is exactly equal to the speed of the thread. These rollers are fluted to facilitate the detachment of the thread from their surfaces.

During the passage of the thread from one bath to another, the thread contacts with or rubs against any suitable means such as a rubber sponge to remove the excess of liquid taken up and to cause it to fall back into the bath. On leaving the bath 8 the thread passes over one or more driers 10 similar to those used in paper-making.

A special device is provided with the object of enabling the thread to be caused to take several turns round the same drier as shown by Figs. 4 and 5. After each revolution the thread leaves the drier and passes around a power-driven shifter roller 11 that gives it a fresh position on the drier 10 not coinciding with that of the previous revolution. A number of the rollers 11 are shown supported on a shaft 11^a and, as will be seen, the said rollers maintain the coils of thread in separated condition so as to facilitate dry-

ing of the same and maintain them in their desired individual construction. The drier 10 is mounted to overhang on a pillar 16, and is provided with an interior warming device 15 through which circulates any suitable heating medium. The drier, as hereinbefore noted, is a well known construction but is exceptionally effective in drying the threads when the shifter rollers 11 are used therewith 10 as shown. On finally leaving the drier or driers the thread is wound on a bobbin 12, the twisting and skeining being afterward effected by the ordinary means. Several threads can be manufactured simultaneously 15 on the same machine by means of the same arrangements, by keeping such threads separate.

The rollers 9 are mounted to over-hang at one end of their axis 13 (Figs. 2 and 3). One 20 or more of the flutings as shown by Fig. 2 is or are prolonged beyond their front faces to form one or more projecting knobs 14, five or six millimeters high. The object of these knobs is to facilitate the process of starting. 25 The workman, holding the thread in his right hand, takes hold of it again with his left hand so as to follow approximately the rate at which it is being fed forward. At the same time he brings this thread close to the 30 roller 9 on which it has to run and without letting it go he causes it to be engaged by one of the knobs. The thread mounts at once of its own accord onto the flutings and the workman, always keeping the end in his 35 hand continues to follow the thread as it is supplied, taking it up again and passing on to the following roller. A workman of average skill is easily able in a short time to pass the end of the thread over the whole machine 40 when running at a speed of 60 to 80 meters per minute.

Having thus described and ascertained the nature of the invention and in what manner the same may be performed, what is 45 claimed is:

1. In an apparatus of the class specified, a viscose reservoir, a plurality of successive baths, one of the baths adjacent to the reservoir having a draw-plate means therein, a compressed air duct communicating with the reservoir, a tubular connection between the reservoir and draw-plate means for feeding the latter with viscose, and a drier having shifter rolls coöperating therewith to separate 50 the coils of viscose thread passing from the final bath to the said drier.

2. In an apparatus of the class specified, the combination of a plurality of baths, one of which has draw-plate means, means for 60 supplying viscose to the draw-plate means under air pressure, and a rotatable drier for directly receiving the viscose thread as it leaves the final bath.

3. In an apparatus of the class specified, 65 the combination of a plurality of baths, one

of which has draw-plate means, means for supplying viscose to the draw-plate means under air pressure, and a rotatable drier for receiving and drying the viscose thread after it passes directly from the final bath and provided with means for causing the thread to take several turns therearound. 70

4. In an apparatus of the class specified, a plurality of baths containing coagulating, acidulated washing and neutralizing liquids, 75 the coagulating bath having draw-plate means therein, means for supplying viscose to the draw-plate means under pressure, directing rollers between the several baths having fluted surfaces, and a drier on which the 80 thread is wound after leaving the final bath.

5. In an apparatus of the class specified, a plurality of baths containing coagulating, acidulated washing and neutralizing liquids, 85 the coagulating bath having draw-plate means therein, means for supplying viscose to the draw-plate means under pressure, directing rollers between the several baths having surface flutings partially provided with projecting knob means, and a drier over 90 which the thread passes from the last bath.

6. In an apparatus of the class specified, a plurality of thread treating baths containing coagulating, acidulated washing and neutralizing liquids, means for supplying viscose to 95 and forming a viscose thread in one of the baths, the thread being drawn through the successive baths, a plurality of rollers interposed between the baths and having a circumferential speed similar to that of the 100 speed of movement of the thread passing thereover, and a rotatable drier for receiving the thread directly from the final bath and completing its formation by coiling the same.

7. In an apparatus of the class specified, 105 the combination of a plurality of baths containing coagulating, acidulated washing and neutralizing liquids, means for supplying viscose to and forming a viscose thread in one of the baths, the viscose thread being drawn 110 regularly through the successive baths, and a rotatable drier for receiving the thread directly from the final bath and operating to cause the thread to take several turns there-around while in wet condition to dry the 115 individual coils of the thread.

8. In an apparatus of the class specified, 120 the combination with viscose thread forming means and coagulating washing, and neutralizing baths through which the viscose thread is successively drawn, of a drier around which the thread is wound, the drier directly receiving the thread from the final bath, the drier being provided with means for holding the coils of the thread separated thereon. 125

9. In an apparatus of the class specified, 130 the combination of a plurality of baths successively containing coagulating, acidulated washing and neutralizing liquids, the final bath containing the neutralizing liquid,

means for supplying viscose to and forming a viscose thread in the first bath, the thread being drawn through the successive baths, and a drier to receive the thread directly from the final bath, the neutralizing liquid in the final bath preventing the thread from adhering to the drier.

10. In an apparatus of the class specified, the combination of a plurality of baths for treating a viscose thread, a plurality of direction rollers interposed between the baths and

having surface flutings partially projected in the form of guiding knobs, and means for receiving the thread after it passes from the final bath.

In testimony whereof I have hereunto set my hand in presence of two subscribing witnesses.
